UNITED STATES PATENT OFFICE.

WILLIAM H. SCOTT, OF ST. LOUIS, MISSOURI.

ENGINE.

SPECIFICATION forming part of Letters Patent No. 625,471, dated May 23, 1899.

Application filed June 6, 1898. Serial No. 682,645. (No model.)

To all whom it may concern:

Be it known that I, WILLIAM H. SCOTT, a citizen of the United States, residing at the city of St. Louis, State of Missouri, have invented 5 a certain new and useful Improvement in Engines, of which the following is a full, clear, and exact description, such as will enable others skilled in the art to which it appertains to make and use the same, reference being 10 had to the accompanying drawings, forming part of this specification, in which—

Figure 1 is a vertical longitudinal sectional view through my improved engine. Fig. 2 is a horizontal sectional view of the same, 15 and Figs. 3, 4, 5, and 6 are diagrammatic views illustrating the engine in its different positions.

This invention relates to a new and useful improvement in engines of that type wherein 20 pistons are arranged at right angles to each other, said pistons operating in suitable cylinders, into and from the ends of which is admitted and exhausted the motive fluid which causes the vertical piston to move 25 practically in a circle, thus communicating rotary motion to a crank-shaft, upon which said vertical piston is mounted. The closed cylinder for the vertical piston has two open-ended cylinders projecting from each side, 30 which lateral cylinders coöperate with two horizontally-arranged plungers or fixed pistons. This particular type of engine is not broadly new. In the patent to Newall and Blyth, No. 441,578, of April 16, 1889, is shown 35 such a type of engine, in which a hollow ported crank admits and exhausts pressure to and from the different ends of the cylinders. Another adaptation of this type of engine is illustrated in the patent to Tower, 40 No. 444,259, of January 6, 1891, wherein rotary valves are oscillated to admit and exhaust pressure to and from the ends of the several cylinders.

An object of this present invention is to 45 dispense with the use of separate valves for the cylinders, as shown in the above two patents, and to provide suitable ports to co-operate with the pistons in the cylinders, whereby said pistons act as valves to admit 50 and exhaust pressure to and from the ends of their associate cylinders.

Another object is to provide suitable ports

which conduct the motive fluid to the ends of the cylinders, whereby full pressure is admitted to the cylinders for such time as the 55 pressure may be effective, after which the pressure is exhausted, giving the same full time for such exhaust. The full area of the ends of the pistons is susceptible to pressure during such period of time as the pressure 60 may be effective thereon. Thus the full working capacity of the engine is developed, and there is no back kick or halting in its work.

With these objects in view the invention consists in the construction, arrangement, 65 and combination of the several parts, all as will hereinafter be described, and pointed out in the claims.

In the drawings, A indicates a suitable casing, through the upper portion of which are 70 preferably formed ports, leading from a supply-pipe B into and through plungers or fixed pistons C and C', mounted on suitable heads D and D', bolted to the sides of the casing.

E indicates a crank-shaft mounted in suitable bearings to one side of the casing A, on the crank-pin of which is carried a double-headed piston F, which I shall term the "vertical" piston. This vertical piston operates in a closed cylinder G, from the sides of which 80 extend open-ended cylinders H and H', co-operating with the plungers or fixed pistons C and C', respectively. Plungers or fixed pistons C and C' are provided with two packing-rings c, between which are arranged open- 85 ings for the passage of fluid into that portion of the open-ended cylinders H and H' between said packing-rings. The vertical piston F is likewise provided with two packing-rings f, at its upper and lower ends, between which are 90 formed spaces, which are practically filled with pressure at all times.

Ports 1 and 1^a lead from the ends of cylinders H and H' to the upper and lower chambers of the cylinder for the vertical piston. 95 These ports admit and exhaust pressure to and from the ends of the vertical piston.

Ports 2 and 2^a lead from cylinders H and H' to the vertical cylinder between the rings f on the ends of said vertical piston, whereby 100 steam-pressure is constantly in said ports and in the space between said rings.

Ports 3 and 3^a lead from the inner ends of cylinders H and H' into the cylinder for the

vertical piston. The inner rings f on the vertical piston coöperate with ports 3 and 3^a to admit and exhaust pressure to and from chambers in the cylinders H and H' at the inner 5 ends of the plungers C and C'.

The operation of the engine is clearly shown in Figs. 3 to 6, wherein the diagrammatic views illustrate the position of the parts between quarters—that is, the crank-shaft is at 10 an angle of forty-five degrees and in four different positions in the four views. In Fig. 3 the pressure is entering through the two plungers C and C' and fills the space between the packing-rings on the inner ends of said plungers. Through the ports 2 and 2^a the pressure enters into the spaces 4 between the packing-rings on the vertical piston, which spaces 4 are in constant communication with the live pressure. The pressure is admitted 15 to the top of the vertical piston, forcing the same downward. At the same time pressure from lower chamber 4, through port 3, against the plunger C, forces the movable parts laterally to the left. The chamber at 20 the lower end of the vertical piston is exhausting now through port 1^a and the open end of cylinder H' into casing A, when said exhaust steam is carried away by a suitable pipe x. In front of plunger C' the chamber is exhausting 25 through port 3^a, the space between the inner rings on the vertically-movable piston, and out through an opening g in the cylinder G, through which the crank-pin passes, as is well understood. When in the housing or 30 casing A, this steam can be led through pipe x to the exterior or any desirable point. The engine is moving in the direction of the arrows shown in the figures, and the next position between quarters is that illustrated in 35 Fig. 4, wherein it will be seen that the space in front of plunger C is now exhausting and the live steam is being admitted to the chamber in front of plunger C'. With respect to the vertical piston its upper end is still receiving 40 pressure, while its lower end is still exhausting. The next position is shown in Fig. 5, where the opposite plungers are receiving and exhausting, as in Fig. 4; but the outer ring c on plunger C' has passed port 45 1^a, so that pressure is now being admitted beneath the vertical piston, while the outer ring on plunger C has passed inside the port 1, so that the chamber above the vertical piston is being exhausted. Fig. 6 shows the next 50 position, in which the vertical piston is being moved upward, the pressure being exhausted from its upper end and admitted to its lower end, while pressure is also being admitted in front of plunger C and is being exhausted in 55 front of plunger C'. 60

From the above it will be seen that the vertical piston carries spaces constantly open to steam-pressure. The plungers also carry spaces constantly open to steam-pressure. 65 Through the medium of the outer rings on the plungers coöoperating with the ports 1 and 1^a pressure is alternately admitted and ex-

hausted to and from the ends of the vertical piston, and through the medium of the inner rings f on the vertical piston coöperating with 70 the ports 3 and 3^a pressure is alternately admitted and exhausted to and from the chambers in front of the plungers C and C', the plungers thus acting as valves for the vertical piston and the vertical piston acting as a 75 valve for the lateral plungers.

The construction is simple and cheap, and the surface areas at the ends of the vertical piston and plungers are exposed to active pressure as long as such pressure is effective, 80 and when such pressure is no longer effective it is exhausted, being given a length of time corresponding to its admission. By reason of this the engine is perfectly balanced and will run smoothly, utilizing the full extent of 85 the exposed piston areas and developing considerable power, there being absolutely nothing in the construction to retard the movement of the engine in the direction in which it is to rotate. Furthermore, there are no 90 dead-centers, and upon the admission of the steam through the plungers C and C' the engine is self-starting.

I am aware that minor changes in the construction, arrangement, and combination of 95 the several parts of my engine can be made and substituted for those herein shown and described without in the least departing from the nature and principle of my invention.

Having thus described my invention, what 100 I claim, and desire to secure by Letters Patent, is—

1. In an engine, the combination with a housing having fixed inwardly-projecting hollow pistons, of packing-rings on said pistons 105 between which fluid-pressure is constantly present, open-ended cylinders fitting over said pistons and provided with suitable ports, a vertical cylinder between said open-ended cylinders, into the ends of which vertical cylinder lead ports from the open-ended cylinders, ports 2 and 2^a which are constantly open to the pressure between the rings on said fixed pistons, a vertical piston mounted in the vertical cylinder and formed with steam-spaces 110 which are constantly open to ports 2 and 2^a, ports 3 and 3^a which lead from the inner ends of the open-ended cylinders into the vertical cylinder, and a crank-shaft upon which the vertical piston is mounted, substantially as 115 described.

2. The combination with fixed pistons formed with live-steam spaces therearound, of open-ended cylinders arranged thereon, a closed cylinder arranged at right angles to 120 said open-ended cylinders and between the same, a piston in said closed cylinder, carrying live-steam spaces at its ends, which are in constant communication with the steam-spaces of the fixed pistons, a crank-shaft upon 125 which said piston is mounted, and suitable port arrangements, whereby the fixed pistons act as valves for the vertical piston, steam from their spaces driving the vertical piston, 130

and the vertical piston acts as a valve for the chambers in front of the fixed pistons, steam from the spaces of the vertical piston entering said chambers and being exhausted therefrom, substantially as described.

3. In an engine, the combination with fixed pistons C and C' carrying rings c, of open-ended cylinders H and H' coöperating therewith, a closed cylinder G arranged between 10 and at right angles to the cylinders H and H', a port 1 leading from cylinder H to the upper end of the closed cylinder G, a port 1^a leading from the cylinder H' to the lower end of closed cylinder G, ports 2 and 2^a which are 15 constantly open to steam-pressure and lead from the cylinders H and H' to the closed cylinder G, a piston in said closed cylinder car-

rying rings between which ports 2 and 2^a lead, respectively, to supply spaces between said rings with fluid-pressure, ports 3 and 3^a which 20 lead from the inner ends of the open-ended cylinders and coöperate with the inner rings on the piston in the closed cylinder, and a crank-shaft on which said piston in the closed cylinder is mounted, substantially as de- 25 scribed.

In testimony whereof I hereunto affix my signature, in the presence of two witnesses, this 21st day of May, 1898.

WILLIAM H. SCOTT.
